US00D663293S

(12) **United States Design Patent**
MacManus et al.

(10) **Patent No.:** US D663,293 S
(45) **Date of Patent:** ** Jul. 10, 2012

(54) **BASE STATION ENCLOSURE**

(75) Inventors: **Gerard MacManus**, Foothill Ranch, CA (US); **Greg Veintimilla**, Mission Viejo, CA (US); **Khurram Sheikh**, San Clemente, CA (US); **Stephen J. Sifferman**, Santa Clara, CA (US)

(73) Assignee: **Powerwave Technologies, Inc.**, Santa Ana, CA (US)

(**) Term: **14 Years**

(21) Appl. No.: **29/411,061**

(22) Filed: **Jan. 16, 2012**
